UNITED STATES PATENT OFFICE.

SAMUEL N. McCLEAN, OF CLEVELAND, OHIO.

MEANS FOR CONTROLLING THE RECOIL AND MUZZLE-BLAST OF GUNS.

SPECIFICATION forming part of Letters Patent No. 785,975, dated March 28, 1905.

Application filed July 1, 1904. Serial No. 214,996.

To all whom it may concern:

Be it known that I, SAMUEL N. McCLEAN, a resident of Cleveland, Ohio, have invented a new and useful Improvement in Means for 5 Controlling the Recoil and Muzzle-Blast of Guns, which invention is fully set forth in the following specification.

This invention relates to firearms, and more particularly to the control of the gas-current in double-barreled guns, such as the ordinary double-barrel shotgun, and as the result of the control of the gas-current effecting the control of the recoil and the muzzle-blast and minimizing the violence, character, and extent of the zone of disturbance at the muzzle of the barrel due to said muzzle-blast.

Prior to the date of the present invention I have devised a means of controlling the gas-current whereby the kick or recoil of the gun 20 and the blast of the gases of discharge at the muzzle are diminished and the report of the discharge largely decreased, which means, briefly stated, consist of areas of resistance formed on the interior surface of the barrel, 25 associated with which areas are a series of vents for the escape of the powder-gases.

In using guns, such as double-barrel shotguns, for sporting purposes the blast of the powder-gases issuing from the muzzle of the 30 barrel sets up a violent disturbance, extending over a considerable zone around the muzzle, which very much interferes with the accuracy of the flight of the shot or other form of projectile, while the recoil or kick of the 35 barrel tends to throw the muzzle of the gun off of the line of sight and also has a tendency to cause the sportsman to shrink or flinch from the punishment due to the recoil. These are serious elements, interfering with the accuracy of the gun and tending to materially 40 interfere with the readiness with which the sportsman may discharge the second barrel immediately after the first.

The object of the present invention is to so 45 effect the control of the gas-current before it issues from the muzzle of the barrel as to partially or entirely eliminate the recoil, whereby the punishment to the sportsman will be avoided, and also as the result of this 50 control of the gas-current the zone of disturbance

around the muzzle will be greatly reduced, not only in area, but also in the violence of the disturbance, thereby largely avoiding the injury to the line of sight due to this cause.

55

A more injurious result of the violent disturbance set up by the gas-current at the muzzle of the barrel in guns as heretofore constructed is the effect which this violent disturbance has upon the projectile immediately after it leaves the muzzle of the barrel, tending to interfere with the accuracy of its revolution in rifled arms and tending to materially deflect it from its course in smooth-bore guns, such as shotguns, and one of the 60 most important beneficial results due to my invention is that the projectile as it leaves the muzzle of the gun is not subjected to the violent cross-currents and other disturbance due to the muzzle-blast, since this blast is so 65 largely reduced and its violent character so much diminished that the projectile continues on its line of flight practically as it was directed by the barrel.

70

It has been found that when the violence 75 and extent of the area of disturbance has been largely eliminated and the force of the recoil counteracted the accuracy of the flight of the projectile from the instant it leaves the muzzle of the gun is much increased and its trajectory greatly flattened, thereby contributing to the accuracy with which the sportsman 80 can use the weapon.

In carrying out my invention I provide the interior surface of each barrel of the double-barreled gun with areas of resistance to the forward movement of the gases of discharge and associate with these areas of resistance vents for the gases arrested by said areas. Preferably these areas of resistance are in the 85 form of annular grooves cut or otherwise formed on the interior surface of the barrel, the metal of the barrel, if necessary, being thickened for this purpose. In some cases, where it is deemed undesirable to increase 90 the thickness of the metal between the two gun-barrels, the grooves are formed only in the thickened walls of the barrel and are allowed to gradually and almost entirely disappear when they reach that portion of the bar- 100

rel constituting the midrib or dividing metal between the barrels. This results in a groove which is annular in cross-section, with the exception that it is flattened—*i. e.*, is of diminished depth along the portion of the midrib or dividing metal between the barrels. In other instances the metal forming the partition between the two barrels is considerably thicker than that of guns as heretofore constructed, and the grooves are annular in form throughout their entire extent—*i. e.*, they are without the flattened portion which occurs in the groove where the dividing metal between the barrels is not increased in thickness. The 15 grooves may be formed in the two barrels in pairs located in the same transverse plane, and this is the construction usually employed where the midrib of the barrel is not thickened over that of the ordinary construction. 20 On the other hand, the grooves or areas of resistance on the interior of the barrel may be formed in staggered relation—*i. e.*, the groove or area of resistance in one barrel is placed opposite an intervening space in the 25 adjacent barrel, so that no two grooves or areas of resistance in the two barrels will lie in the same transverse plane. By this means the metal or midrib between the barrels is not weakened to such an extent as would occur if 30 the grooves were opposite each other. In fact, the grooves themselves may thereby be made much deeper than would be practicable if the grooves in the two barrels were permitted to lie two in any transverse plane. 35 For the purpose of utilizing the reaction of the gases passing out of the vents associated with the areas of resistance a considerable number of the vents are inclined rearward, preferably at an angle of about forty-five degrees to the axis of the barrel. All of the 40 vents may, if desired, be thus inclined rearward; but in order to avoid a backward blast of the gases, which would prove to be detrimental if not injurious to the gunner, I preferably arrange some of the vents associated with the areas of resistance at an angle of about forty-five degrees to the axis of the barrel, and others are radial to the barrel. Preferably these radial and rearwardly-inclined vents alternate with each other, so as to distribute the escaping gases over a large space, and thus prevent a too great concentration at any particular point. For the purpose of permitting the escape of the gas at that side of the 55 barrel which is adjacent to the other barrel I preferably pass vertical holes or openings through the midrib or dividing-partition and permit a portion of the vents associated with the areas of resistance to discharge their gas into these vertical openings.

In some instances the radial vents and the rearwardly-inclined vents associated with the areas of resistance are so arranged that the jets of gas issuing from said vents cross or interfere with each other, thereby serving to

break up the respective jets and disseminate the same over a greater area. The result of this is that the sound of the discharge, as well as the violence of the blast issuing from the jets, is much diminished.

While the areas of resistance and their associated vents are formed in the walls of the gun-barrel proper, it is not to be understood that the gun-barrel itself or the pair of gun-barrels are necessarily integral. The areas 75 of resistance and the vents associated therewith may be either formed in an integral portion of the barrels or they may be formed in a portion of the barrels which is detachably secured to the other or rearward portion of 80 the barrels. In either event the result secured is the same—*i. e.*, the tension and velocity of the powder-gas within the barrel is largely reduced before the charge of shot or other projectile issues from the muzzle of the barrel 85 and during the time in which the barrel exerts the usual control and function of the barrel over said charge of shot or other form of projectile.

It will be apparent to those skilled in the 90 art that the invention may be embodied in various mechanical forms, and for the purposes of illustrating said invention I have shown in the accompanying drawings two of the forms which the same may assume. It is to be understood, however, that said drawings are for the purpose of illustration only and not for the purpose of defining the limits of the invention.

Referring to said drawings, Figure 1 is a 100 horizontal section through the muzzle portion of a double-barreled shotgun, showing the areas of resistance in the two barrels arranged in pairs, each member of the pair being in the same transverse vertical plane. Fig. 2 is 105 a section on the line 2-2 of Fig. 1. Fig. 3 is a horizontal section through a double-barreled gun, having a thickened midrib between the barrels, the areas of resistance in the two barrels being shown in different transverse 110 vertical planes. Fig. 4 is a transverse vertical section on the line 4-4, Fig. 3; and Fig. 5 is a broken detail illustrating the arrangement of the vents; and Fig. 6 is a horizontal section through the forward part of a double-barreled gun, showing another construction of 115 resistance-surfaces and vents associated therewith. Fig. 7 is a section on line 7-7, Fig. 6; and Fig. 8 is a section on line 8-8, Fig. 6.

Referring to Figs. 1 and 2 of the drawings, 120 1 is the forward portion of a double-barreled shotgun, which is preferably provided with a thickened portion 3 near the muzzle or forward end of the barrel, and within this thickened portion are formed areas of resistance 125 in the shape of annular grooves 5. In this case the midrib 6 between the barrels is of the same thickness as that in the ordinary construction of a double-barreled gun, and the annular grooves 5 are of even depth around 130

the entire interior of the barrel, except that portion of the grooves adjacent to the midrib 6, at which portion the grooves gradually diminish in depth and may entirely disappear, 5 so that in viewing the grooves in transverse section, as shown in Fig. 2, there will be a flattened portion 7.

Associated with the grooves 5, and preferably with each of said grooves, is a series of 10 rearwardly-inclined vents 8 and also a series of radial vents 9. While one of the areas of resistance might, if desired, be provided with rearwardly-inclined vents only and the next adjacent area of resistance be provided with 15 radial vents only, I prefer to provide each groove with both rearwardly-inclined and radial vents which alternate with each other, as shown in Figs. 1 and 5. When thus constructed, the radial vents 9 extend outwardly 20 from the bottom or deepest portion of the groove immediately adjacent to the forward wall thereof, while the rearwardly-inclined vents 8 preferably extend from another wall, which is here shown as inclined forward and 25 outward in the walls of the barrel, the exterior opening of such rearwardly-inclined vents being forward of the series of radial vents formed in the groove next to the rear and alternating therewith, all of which will 30 be clearly understood by an inspection of Figs. 1 and 5.

Referring to Fig. 8, and considering any two of the grooves in a single barrel, it will be observed that the rearwardly-inclined vents 35 of one groove are substantially in longitudinal alignment with the radial vents of the groove immediately to its rear, so that the gas issuing from the rearwardly-inclined vent crosses or interferes with the gas issuing from 40 the radial vent of the rear groove. This results in a very material breaking up and dissemination of the gas issuing from each of the vents, so that the total amount of gas discharged from the vents associated with the 45 areas of resistance within the barrel is more evenly distributed than would be the case if the various jets would not cross or interfere with each other—*i. e.*, in a construction such as shown in Figs. 1 and 3.

50 As shown in Figs. 1 and 3, the areas of resistance and the vents associated therewith are formed to the rear of the muzzle portion 10 of the gun and in an integral part of the barrels. As above stated, these areas of resistance may, if desired, be formed in a portion of the barrel which is detachably attached to the other portion thereof. Such a construction is shown in Fig. 1. Moreover, in Fig. 3 the midrib is shown much thicker than 55 the construction of Fig. 1, such rib being indicated at 11, and in order to avoid a too great weakening of the metal of the rib between the barrels and to permit the formation of grooves of greater depth there are formed 60 annular grooves 12, which are arranged in

staggered relation or in different transverse planes, as will be readily understood by an inspection of said Fig. 3. Passing vertically through the thickened midrib 11 are perforations 13, preferably one for each of the 70 grooves or areas of resistance in each barrel. These perforations 13 communicate with each of the grooves 12 either by themselves being formed so as to just cut the periphery of the groove, as shown in Fig. 2, or, if desired, 75 there may be a separate channel leading from the groove 12 to the perforation 13. This perforation affords an escape for the gas, which is arrested or which impinges upon that portion of the grooves or the areas of resistance opposite the thickened midrib. 80

It will be observed that by forming the areas of resistance and the vents associated therewith in the walls of the barrel itself, whether said barrel is integrally or sectionally formed, 85 the control of the gas-current is effected and its violence, tension, and velocity greatly diminished during the time in which the shot or other form of projectile is within the gun-barrel and still under the barrel's control. This 90 is particularly exemplified in the construction shown in Fig. 6, wherein the portion of the barrel in front of the forward area of resistance is shown as slightly contracted or "choked," 95 as indicated at 14 in said figure, in the manner well known in the art. The effect of the choke upon the charge occurs after the areas of resistance and their associated vents have acted to effect a complete control of the gas-current, so that when the concentration of a 100 charge of shot is effected by the choke it will not again be scattered by the disturbance heretofore existing just forward of the muzzle. It will also be noticed in connection with Figs. 6 and 7 that the areas of resistance 15 are not 105 only flattened or decreased in depth adjacent to the midrib, but that they are likewise flattened or decreased in depth on that side of the barrel diametrically opposite the midrib, as shown at 16 in said figure, and that the 110 vents associated with the areas of resistance may be omitted along a portion of the extent of the barrel, as shown at 17. The object of this is to avoid any possible tendency of the gases issuing from the side of the barrel to 115 throw the same to one side or the other, as the case might be, by the reaction of the gases against the air on the outside.

What is claimed is—

1. A gun-barrel having an area of resistance 120 to the gas-current on its interior, vents associated with said areas and a contraction or "choke" of the bore in advance of said area of resistance.

2. A gun-barrel having an area of resistance 125 to the gas-current on its interior, and a plurality of vents associated with said area of resistance and a contraction or "choke" of the bore in advance of said area of resistance.

3. A gun-barrel having an area of resistance 130

1 to the gas-current on its interior, a plurality of rearwardly-inclined vents associated with said area of resistance and a contraction or "choke" of the bore in advance of said area 5 of resistance.

4. A gun-barrel having an area of resistance to the gas-current on its interior, a plurality of radially-inclined vents associated with said area of resistance, and a contraction or 10 "choke" of the bore in advance of said area of resistance.

5. A gun-barrel having an area of resistance to the gas-current on its interior, a plurality of rearwardly-inclined vents and a plurality 15 of radial vents associated with said area of resistance, and a contraction or "choke" of the bore in advance of said area of resistance.

6. A double-barreled gun having a plurality 20 of areas of resistance in each barrel, said areas in the two barrels being in staggered relation to each other.

7. A double-barreled gun having a plurality 25 of areas of resistance in each barrel, said areas in the two barrels being in staggered relation to each other, and lateral vents associated with said areas of resistance.

8. A double-barreled gun having a plurality 30 of areas of resistance in each barrel, said areas in the two barrels being in staggered relation to each other, and radial lateral vents associated with said areas of resistance.

9. A double-barreled gun having a plurality 35 of areas of resistance in each barrel, said areas in the two barrels being in staggered relation to each other, and rearwardly-inclined lateral vents associated with said areas of resistance.

10. A double-barreled gun having a plurality 40 of areas of resistance in each barrel arranged in staggered relation to each other in the two barrels, and a plurality of alternately-arranged radial and rearwardly-inclined vents associated with said areas of resistance.

11. A gun-barrel having an area of resistance formed on its interior and a plurality of 45 alternately-arranged radial and rearwardly-inclined vents associated with said area of resistance.

12. A gun-barrel having a groove on its interior said groove being flattened or having 50 its depth decreased on one side of the barrel.

13. A gun-barrel having an area of resistance to the gas-current on its interior, said area being in the form of a groove flattened or of decreasing depth on opposite sides of the 55 barrel.

14. A gun-barrel having a groove on its interior said groove being flattened or having its depth decreased on one side of the barrel, and a plurality of vents associated with said area of resistance.

15. A gun-barrel having an area of resistance to the gas-current on its interior, said area being in the form of a groove flattened or of decreasing depth on opposite sides of the barrel, and a plurality of vents associated with 60 said area of resistance.

16. A double-barreled gun having an area of resistance on the interior of one of its barrels, said area diminishing in cross-sectional area adjacent to the midrib or metal between the 70 barrels.

17. A double-barreled gun having an area of resistance in the form of a groove on the interior of each barrel, said grooves diminishing in depth adjacent the midrib or metal between 75 the barrels.

18. A double-barreled gun having an area of resistance on the interior of each barrel and a vent associated with each area of resistance and passing through the midrib or metal between 80 the barrels.

19. A double-barreled gun having a plurality 85 of areas of resistance to the gas-current on the interior of each barrel, said areas being in staggered relation in the two barrels, and a vent associated with each area of resistance and passing through the midrib or metal between the barrels.

20. A gun-barrel having a plurality of areas 90 of resistance to the gas-current on its interior and a plurality of vents associated with said areas, some of the vents directing jets of escaping gas across or at an angle to jets escaping from other vents.

21. A gun-barrel having a plurality of areas 95 of resistance to the gas-current formed on its interior wall, and a plurality of vents associated with said areas of resistance, vents associated with one of said areas directing the escaping gas at an angle to the line of direction of gas escaping from vents associated with an area of resistance to the rear of said first area of resistance.

In testimony whereof I have signed this specification in the presence of two subscribing witnesses.
